DESIGN FOR A MEDALLION OR SIMILAR ARTICLE

Harold W. Draper, West Orange, N. J., assignor to United States of America, as represented by the Secretary of War

Application May 31, 1946, Serial No. 130,306

Term of patent 14 years

(Cl. D29—2)

To all whom it may concern:

Be it known that I, Harold W. Draper, a citizen of the United States and resident of the city of West Orange, in the county of Essex and State of New Jersey, have invented a new, original, and ornamental Design for a Medallion or Similar Article, of which the following is a specification, reference being had to the accompanying drawings, forming a part thereof.

Fig. 1 is a front elevational view of a medallion, showing my new design.

Fig. 2 is a side view of the same.

It is understood that my design may be embodied in such articles as a medallion, medal, badge, plaque, or sign, without departing from the spirit of my invention.

The essential features of my design are shown in full lines.

I claim:

The ornamental design for a medallion or similar article, as shown and described.

HAROLD W. DRAPER.
